UNITED STATES PATENT OFFICE.

GEORGE BROWNING, OF WILMETTE, ILLINOIS, ASSIGNOR TO CHICAGO FLEXIBLE SHAFT COMPANY, OF CHICAGO, ILLINOIS, A CORPORATION OF ILLINOIS.

SPRINKLER NOZZLE.

Application filed September 22, 1923. Serial No. 664,159.

This invention relates to sprinkler nozzles, particularly adapted for lawn and garden sprinklers of various types. It is shown as applied to a device of the type having a 5 portable standard and rotating arms from which the water is thrown, but it is equally applicable, as a nozzle, to be applied directly to the end of a hose. It consists of certain features and elements of construction in 10 combination as herein described and shown in the drawings and as indicated in the claims.

In the drawings:

Figure 1 is a side elevation of a portable 15 sprinkler standard of the rotating arm type, fitted with two similar nozzles embodying this invention.

Figure 2 is a vertical medial section showing one of the nozzles adjusted to throw 20 a spray.

Figure 3 is a medial sectional view of the nozzle with the stem broken away showing the parts adjusted to throw a coarse stream of water.

25 Figure 4 is a side elevation of the nozzle partly in section showing it adjusted to position for limiting the flow of water.

Figure 5 is a top plan view of the nozzle.

Figure 6 is a transverse section taken sub- 30 stantially as indicated at the line 6—6 on Figure 4.

Figure 7 is a section at the same plane as Figure 6 but showing the valve member rotated into unlocked position.

35 For purposes of illustration, this nozzle is shown mounted on a rotary lawn sprinkler comprising a base, 1, upon which a hub, 2, is mounted for rotation about a vertical axis and carries radial arms, 3, through which the 40 water is conducted to the nozzles mounted in the threaded terminals, 4, of said arms. Each nozzle is attached by means of a threaded base, 5, to which the upright stem, 6, of the nozzle body is swivelly connected by 45 means of a reduced portion, 7, sleeved within the base, 5, and permanently secured by a slight flanging of its lower end at 8. This permits the nozzle body to be rotatively adjusted with respect to the radial arm, 3, 50 for varying the area covered by the sprinkler at any set position and incidentally varying the speed of rotation of the arms on the standard, 1.

The stem, 6, of the nozzle body supports 55 an obliquely disposed barrel, 9, whose bore,

10, is intersected at a point between its ends by the upper end of the bore, 11, of the stem, 6. The flow of water through the bore, 10, is controlled by a valve member having a cylindrical portion, 12, snugly fitted in the bore, 10, and longitudinally slidable therein. From the upper and forward end of the part, 12, a reduced portion or stem, 13, extends into the bore, 10, and terminates in a head whose diameter is slightly less than 60 that of the bore, 10, though it may be substantially equal to the reduced opening, 10^a, at the discharge end of the barrel, 9. With the valve member adjusted as shown in Figure 2 so that the head, 14, stands just outside said opening, 10^a, the water emerging from the nozzle is deflected laterally upon striking the under side of the head, 14, and is thus thrown in a wide spray. With the valve set as shown in Figure 3, 70 this head, 14, is withdrawn downwardly into the bore, 10, and back of the point at which the bore, 11, intersects the barrel, 9, thus permitting a substantially free flow of water from the barrel in a comparatively 75 coarse stream. By setting the valve member as shown in Figure 4, the head, 14, partially closes the bore, 10, and reduces the force and volume of the water though it still emerges 80 in a stream rather than a spray. 85

As shown, the barrel, 9, is provided with five notches, *a*, *b*, *c*, *d*, and *e*, respectively. A detent, 15, formed by the bent end of a flat spring arm, 16, is attached to the rear end of the valve member, 12, by riveting 90 over a reduced terminal of said member at 17, and this detent is adapted to enter any of the aforesaid notches for preventing longitudinal movement of the member, 12. However, since the notches are not circumferential in extent but are formed merely by making straight saw-cuts in the upper convex surface of the barrel, 9, the detent, 15, is radially disengaged from any of them by 95 rotating the valve member, 12, and with it the arm, 16, and detent, 15, through such an angle as that indicated in Figure 7 so that the detent, 15, rides out of the notch onto the smooth cylindrical surface at the side 100 of the barrel, 9. The valve member, 12, may then be slidably adjusted up or down in the inclined barrel, 10, and rotated back through a similar angle to engage the detent, 15, in 105 any other notch. For convenience in manipulating the valve, I provide finger pieces, 110

18, which may be formed of the same flat stock as the arm, 16, and integral with the bent end portion thereof which is secured to the valve member, 12, by the rivet head, 5 17.

In the drawings I have shown five notches so as to provide two positions of adjustment for a wide-spread spray and two positions for a more or less coarse stream. The 10 notch, *a*, corresponding to the position of the head, 14, illustrated in Figure 2, provides for a moderately wide-spread spray while it will be seen that when the head, 14, is drawn back somewhat closer to the mouth 15 of the barrel, 9, and secured by engagement of the detent, 15, in notch, *b*, the water will be more widely deflected as it strikes the underside of the head, 14. Figure 3 shows the valve member withdrawn in extreme 20 position with the detent, 15, in notch, *c*, but it will be seen that if the valve be advanced slightly to bring the detent, 15, into notch, *d*, the head, 14, will be placed in the 25 path of the water entering the bore, 10, from the bore, 11, and will tend to reduce the volume of the stream and also to break it up to some degree so that it will emerge from the nozzle in drops rather than as a solid mass of water.

30 It will be understood that in setting the valve to any position it is not necessary to have the detent laterally registered with the desired notch before rotating the valve back to normal position because the yielding nature of the arm, 16, will permit the detent, 15, to ride on the cylindrical surface of the body, 9, at any point intermediate the notches so that when it arrives at the desired notch it will snap into engagement 35 therewith.

I claim:—

1. In a nozzle comprising a barrel and a valve member longitudinally slidable therein to regulate the discharge, said barrel hav-

ing a plurality of longitudinally separated 45 notches arranged along one side of its external surface, and a yielding detent attached to the valve member engageable with any of said notches selectively, the valve member being rotatable about its longitudinal axis for shifting the detent laterally out of any of said notches, and the surface of the barrel adjacent the notches being smooth for slidably supporting the detent during longitudinal adjustment of the valve 55 member.

2. In a nozzle having a hollow barrel and a hollow stem whose bore intersects said barrel intermediate its ends, a valve member having a portion snugly fitting the bore 60 of the barrel with a reduced portion extending therein, and a terminal head slightly less than the bore of the barrel in diameter, said valve member being longitudinally slidable in the barrel for shifting its 65 head from a position beyond one end of the barrel to a position within said barrel intermediate the other end and the intersection of the bore of the stem; a spring detent attached to said valve member at the 70 end opposite its head and positioned to ride over the surface of the nozzle barrel, said barrel having notches to engage the detent at both limiting positions and another notch for said detent for securing the valve with 75 its head intermediate the discharge end of the barrel and the intersection of the bore of the stem.

3. In the combination defined in claim 1, laterally disposed finger pieces on the valve 80 member formed integrally with the detent and adjacent its point of attachment to the valve.

In testimony whereof, I have hereunto set my hand at Chicago, Illinois, this 13th 85 day of September, 1923.

GEORGE BROWNING.
